United States Patent Office

Des. 207,743
Patented May 23, 1967

207,743

JUG

Bruce L. Roberts, Rossford, Ohio, assignor to Owens-Illinois, Inc., Toledo, Ohio, a corporation of Ohio

Filed July 7, 1966, Ser. No. 2,976

Term of patent 14 years

(Cl. D58—5)

FIG. 1

FIG. 2

The back is a mirror image of the front.

The characteristic features of this design reside in the configuration shown in full lines on the drawing.

I claim:

The ornamental design for a jug, substantially as shown and described.
